UNITED STATES PATENT OFFICE

2,582,884

COOKING RANGE HOOD

Herbert E. Nicol, Milwaukee, Wis.

Application September 30, 1949, Serial No. 118,750

2 Claims. (Cl. 126—299)

1

This invention relates generally to ventilated hoods for collecting and exhausting odors and heated gases of combustion from the top of cooking ranges.

Elimination of obnoxious odors and excessive temperatures occurring in domestic kitchens presents a difficult problem, which conventional methods have failed to satisfactorily solve for several obvious reasons.

To collect and dispose of a comparatively small volume of heated gases arising from cooking food, as well as the actual products of combustion from an open flame, is relatively simple, but difficulty arises from the fact that such heated gases quickly contaminate a large volume of surrounding air that is troublesome to control.

To meet the foregoing condition, large collection hoods, necessarily spaced a substantial distance above the range, and large capacity exhaust blower systems have been employed. Such hoods are objectionable because of their unsightly size, and the fact that by the time the grease-laden gases reach the hood they become sufficiently cooled to cause condensation and accumulation of grease on the inner surface of the hood, which is objectionable from the standpoint of cleanliness and sanitation.

With a large capacity fan or blower, a considerable volume of exhausted air must be replenished by outside air which, during cold weather materially increases the heating load. If replacement air is drawn through other rooms in the building, a partially contaminated circulation is frequently set up to foul the air throughout the structure.

The salient feature of the present invention resides in the provision of a comparatively small compact hood vented by a low capacity blower, or through a natural draft flue, and positioned closely adjacent the top of a cooking range to collect odors and heat of combustion at their source, before they have had opportunity to contact and affect an uncontrollable volume of surrounding atmosphere.

Incidental to the foregoing, a still further object of the invention is to provide the hood with an adjustable transparent front visor to facilitate access to utensils during the cooking operation, and also afford unrestricted view of the work at all times.

In addition to the foregoing, other objects will appear as the description proceeds, and while the accompanying drawing illustrates one complete physical form of the invention constructed in accordance with the best mode so far devised, it is to be understood that changes in the precise em-

2

bodiment of the invention are contemplated within the scope of the appended claims.

In the drawing:

Figure 1 is a perspective view of a typical home kitchen installation consisting of a gas range and matching cabinets, the invention being applied thereto;

Figure 2 is a vertical sectional view through the hood incorporating principles of the present invention, the same being taken on the line 2—2 of Fig. 3; and

Figure 3 is a horizontal sectional view taken on the line 3—3 of Figure 2.

Referring now more particularly to the accompanying drawing, Figure 1 illustrates a conventional gas stove 4, equipped with a top burner grill 5, installed against a kitchen wall 7, between a pair of conforming cabinets 6, which serve as convenient work shelves and storage compartments. Attached to the wall 7, in substantial vertical alignment with the stove 4, is a hood 8 consisting of a rear wall 9 and side walls 10 connected by an arcuate front sector 11. The upper portion of the hood 8 is provided with a partition shelf 12 forming a compartment 13 for housing a motor actuated blower 14, to which an exhaust vent 15 is connected. The compartment 13 is preferably closed by hinged doors 16, to provide access to the blower and simulate adjacent storage cabinets 17.

Pivotedly connected to the side walls 10 of the hood 8, adjacent their rear edges, is a visor 18 comprising a pair of side arms connected by an arcuate front frame 20. The arms 19 and frame 20 are preferably of skeleton structure provided with transparent windows 21 to afford unrestricted view of utensils positioned on the grill 5 and the top plate of the stove. As best shown in Figure 2, the visor 18 is supported in its lower operative position by an inturned lip 11' formed on the lower edge of the arcuate front plate 11. A suitable handle 22 attached to the lower edge of the arcuate frame 20 facilitates raising and lowering the visor 18 to selective adjusted positions, in which the visor is held by frictional pintles or conventional types of counter-balance devices (not shown).

Positioned within the upper portion of the hood 8 and extending rearwardly from a point adjacent the lip 11' is an inclined deflector plate 23 terminating at its upper edge a sufficient distance from the rear of the hood, to provide an elongated opening 24 through which odors and gases are drawn by the blower 14 through an opening 12' formed in the partition shelf 12.

A horizontal plate 25 extends between the front

11 of the hood and the upper edge of the inclined plate 23 to close the top of a compartment 26 defined by the arcuate hood front 11 and the inclined plate 23, into which the visor 18 is raised from its lower operative position.

Obviously, the deflector plate 23 also serves to protect the transparent visor 18 against the effect of concentrated columns of heated air directly above the burner grill 5, when the visor is raised to its top position, shown in dotted lines in Figure 2.

Side panels 23', secured to the back wall 9 of the hood, and spaced slightly from the side walls 10 to provide space for the visor arms 19, support the deflector plate 23. A restricted opening 25', formed in the plate 25, vents the compartment 26 to prevent accumulation of gases within the same.

From the foregoing explanation, considered in connection with the accompanying drawing, operation of the present invention will be apparent, in that odors and heated gases of combustion arising from the stove and collected within the hood 8 will be continuously exhausted by the blower 14, or natural flue draft, through the duct 15 to outside atmosphere.

During normal cooking of odorous food, the visor 18 is adjusted to its lowest position as shown in Figure 2, and because of its close proximity to the top of the stove and burner grill 5, obviously a rising column of heated air surrounding a utensil positioned on the grill 5 (solid line arrow, Fig. 2), as well as odors (wavy arrow) confined within the rising converging column above the utensil, will be entrapped within the visor at their source, and discharged from the top of the hood, by the blower 14, before the same have had sufficient time to contact a large volume of room atmosphere (dotted arrows) and becomes cooled sufficiently to cause condensation on the inner walls of the hood.

During the cooking operation a clear view of the utensils is afforded by the transparent front and side windows 21 of the visor 18, and the handles of the utensils are readily accessible for shifting the same without disturbing the visor. When it is desired to have full access to the cooking utensils, the visor can be quickly lifted to its uppermost position as indicated in dotted lines in Figure 2. When non-odorous operations are performed, such as boiling water and the like, the visor 18 need not be lowered unless it is desired to eliminate radiation of heat from the gases of combustion.

In addition to collecting odors and gases at their source, by means of a comparatively compact

hood and a small capacity blower, or natural flue draft, it will be appreciated that the visor 18 also serves to confine spattering grease occurring during frying operations. Also, because of its convenient location, the interior of the visor is accessible for easy wiping and cleaning of the transparent windows 21.

What I claim is:

1. An apparatus of the character described comprising, a hood for support above a cooking range in close proximity to its burners and comprising a transparent visor pivotally connected to said hood to form a lower front portion of the same, the front of said visor being arcuate in cross section, a deflector plate mounted in said hood forming a compartment for reception of the arcuate front of said transparent visor and serving to protect said visor against concentrated columns of heated air when said visor is swung to raised position, and means for venting said hood to outside atmosphere.

2. An apparatus of the character described comprising, a hood for support above a cooking range in close proximity to its burners and comprising a transparent visor pivotally connected to said hood to form lower front and side portions of the same, the front of said visor being arcuate in cross section, a deflector plate mounted in said hood forming a compartment for reception of the arcuate front of said visor when raised, and an exhaust fan positioned above said deflector plate for venting said hood.
